UNITED STATES PATENT OFFICE.

GEORGE K. HENDERSON, OF INDIANAPOLIS, INDIANA, ASSIGNOR TO INTERNATIONAL PRINTING COMPANY, OF INDIANAPOLIS, INDIANA, A CORPORATION.

CARTON SEALER.

1,424,018.

Specification of Letters Patent. Patented July 25, 1922.

Application filed July 2, 1921. Serial No. 482,079.

To all whom it may concern:

Be it known that I, GEORGE K. HENDERSON, a citizen of the United States, and a resident of Indianapolis, county of Marion, and State 5 of Indiana, have invented a certain new and useful Carton Sealer; and I do hereby declare that the following is a full, clear, and exact description thereof, reference being had to the accompanying drawings, in which 10 like numerals refer to like parts.

This invention relates to a carton or box sealing machine of a semi-automatic type, wherein the knock-down cartons or boxes are placed on forms and their end flaps sealed 15 by clamping them down after adhesive material has been applied, and holding them clamped in position until the adhesion is complete.

The main object of the invention is to provide 20 a semi-automatic device whereby the operator simply places the cartons or boxes in position on the form and arranges the flaps, after which the machine is turned to bring another form into position, which 25 causes the clamping of the flaps and secures them in sealed position until the form again reaches the operator, after which the clamp is automatically released so as to permit the removal of the carton and replacement 30 thereof.

One feature of the invention is to provide a cam means for causing the release of the clamping plates and their complete removal from the form so as to permit the box or 35 carton to be replaced.

Another feature of the invention is the guiding member for causing the sealing plate to return to sealing position after it has been elevated therefrom by the cam 40 member.

The full nature of this invention will be understood from the accompanying drawings and the following description and claims.

45 In the drawings Fig. 1 is a plan view looking down upon the machine. Fig. 2 is a side elevation thereof.

In the drawings there is shown a revolving table 10 pivotally supported upon the 50 standard 11, at about the same height as an ordinary table. The table 10 is free to rotate on said standard, and is revolved thereon by the operator who sits at the point A.

The standard 11 extends up through the 55 table and has clamped to the upper end

thereof a collar 12 upon which is securely mounted, in a stationary position, the cam member 13. The cam member is composed of a supporting web 14 and an outwardly extending projecting flange 15 about the 60 lower edge thereof. It is semi-circular in section and is provided with a downwardly sloping and curving bearing edge 16 which terminates with the bearing edge of the projecting flange 15. 65

Mounted on the table 10 there are a plurality of upright form supporting members 17 upon which are slidably and removably mounted the carton or box forms 18. Said box forms are slidably mounted in the lateral guideways 19 so as to be laterally adjustable thereon, whereby a form of varying widths may be centered beneath the sealing plate. The sealing plates 20 are secured to the lever arms 21 on the end of which are 70 mounted metal weights 22. Said plates are mounted in such a position that, when the arms 21 are horizontal, the plates 21 rest upon the top end of the forms 18, with a cushion 23 between them. Said cushion is 75 secured to the bottom surface of the plate. The arms 21 are hinged at the rear top of the supports 17 by hinges 24, and have extending rearwardly therefrom the cam engaging members 25 which may be rotatably mounted on the extensions 26, secured to the arms 21. The cam engaging members 25 are provided with an annular flange 27 at their rear 80 end. Each of the forms is provided with adjustable guide members 28 which enable 85 the operator to quickly slide the carton on the form and guide it in position thereon.

Beneath the cam member 13 there is mounted a guide member 29 which is rigidly secured to the standard 11 by the collar 30. 90 The member 29 is provided with an upwardly extending flange 31 which is so curved and positioned as to engage the cam engaging members 25 when the arms 21 are in tilted position, as shown at the left of 100 Fig. 2, and cause said members 25 to be slightly elevated sufficient to permit the weight 22 to bring the arm 21 downwardly in clamping position.

The operation of the device is as follows: 105 The operator sitting at the point A places a carton or box 32 to be sealed upon the form 18, and places the sealing flaps in closed position. During this operation the clamping plates 20 are held in up-right position by 110

the engagement of the members 25 with the projecting flange 15. While in this position, the remaining cartons are under pressure of the clamping plate and the weight 22. After properly positioning the carton and flaps and applying suitable adhesive, the operator turns the machine a one quarter revolution, causing the member 25, which is extending downwardly, to engage the upturned flange 31 of the guide member 29 so as to force it outwardly as its movement is permitted by the cam 13. The weight 22 then causes the arm 21 to drop into horizontal position, and the clamping plate 20 rests upon the sealing flaps under the pressure of the weight 22. During this quarter movement of the table the form on the right approaches the operator. The engaging member 25, connected with said plates, engages the downwardly curved edge 16 of the cam 13, causing the clamping plate to be elevated. Upon said form coming in position opposite the operator, the said member 25 is then engaged by the outwardly extending flange 15 which forces the arm 21 to substantially an up-right perpendicular position. The clamping plate is thereby moved from in the way of the operator so as to permit free access to the form, after which it is actuated in the same manner as above set forth. It will, therefore, be obvious that it is only necessary for the operator to replace the boxes or cartons on the form, arrange the flaps and turn the table, no attention being needed to operate the clamping plates. The clamping plates are, as above described, entirely operated and controlled by the movement of the table.

The invention claimed is:

- 40 1. A sealing machine for paper receptacles having means for supporting a receptacle, means for clamping and sealing said receptacle under pressure, and a separate means for actuating said clamp and sealing means for causing the same to automatically release said receptacle for permitting its removal and replacement, and thereafter causing said clamping and sealing means to be automatically brought to operative position.
- 45 2. A sealing machine for paper receptacles having means for supporting a receptacle, means for clamping and sealing said receptacle under pressure, means for actuating said clamping and sealing means for causing the same to automatically release said receptacle for permitting its removal and replacement, and means for thereafter causing the clamping and sealing means to be automatically brought to operative position
- 50 60 by the relative movement between said clamping and sealing means and said last mentioned means.
- 55 65 3. A sealing machine for cartons, boxes and the like, comprising a support, a plurality of receiving forms mounted on said

support, means for clamping and sealing said cartons thereon, a cam member adapted to actuate said sealing and clamping means for releasing said cartons, and means for automatically causing said means to engage 70 said carton after being released therefrom.

4. A sealing machine for cartons, boxes and the like comprising a movable support, a plurality of forms mounted on said support for receiving the cartons, clamping and sealing arms mounted in connection with said forms for clamping and sealing said cartons, and an annular cam member provided with a bearing surface extending from the upper portion to the lower portion thereof and terminating in a radially extending bearing surface, substantially as described.

5. A sealing machine for cartons, boxes and the like comprising a movable support, a plurality of forms mounted on said support for receiving the cartons, clamping and sealing arms mounted in connection with said forms for clamping and sealing said cartons, a weight mounted on the end of each of said arms, and an annular cam member 85 centrally positioned on said support provided with a bearing surface extending from the top to the bottom portion thereof for engaging the guide portion of said clamp and causing it to tilt upon its pivot, and a 90 radially extending bearing surface for engaging said arm and forcing it to substantially an upright position.

6. A sealing machine for cartons, boxes and the like comprising a rotatable support, 100 a plurality of forms mounted on said support for receiving the carton, clamping and sealing arms pivotally mounted in connection with said forms for clamping and sealing said carton, a weight mounted on the 105 end of each of said arms, an annular cam member provided with a downwardly extending bearing surface extending from the upper portion to the lower portion thereof and terminating in a radially extending 110 bearing surface in position to be engaged by one end of said arms for causing the same to tilt about their pivot points for releasing said cartons, and a flanged member mounted in connection with said cam member for engaging the opposite side of the ends of said arms for causing the same to be tilted back into engaging position after being released by said cam.

7. A sealing machine for cartons, boxes 120 and the like, comprising a support, a plurality of forms mounted on said support, means for clamping and sealing said cartons, a cam member adapted to actuate said sealing means to permit replacement of cartons to be sealed, and a guide member adapted to actuate said sealing means in connection with said cam member for causing the engagement and sealing thereof after replacement of the cartons.

8. A sealing machine for cartons, boxes and the like, comprising a standard, a support rotatably mounted on said standard, a plurality of forms mounted on said support, means for clamping and sealing said cartons, a cam member fixedly mounted on said standard adapted to engage and actuate said sealing means through the relative movement between said cam member and rotatable support to permit replacement of cartons to be sealed, and a guide member fixedly secured to said standard and so positioned as to engage said clamping and sealing means to cause them to engage and clamp said cartons after the same have moved past said cam member.

9. A sealing machine for cartons, boxes and the like, comprising a standard, a support rotatably mounted on said standard, a plurality of forms mounted on said support, an arm pivoted on said support, one end of which is positioned to engage and clamp one of said cartons, a weight mounted thereon for exerting a downward pressure on said carton when said arm is in horizontal position, a cam member secured to said standard in position to be engaged by the other end of said arm for causing the elevation thereof to a substantially vertical position so as to permit replacement of a carton to be sealed, and a guide member secured on said standard in position to engage the downwardly extending end of said

arm and cause the same to move to a horizontal position as it passes said cam member upon the rotation of said supporting means, for causing the engagement and clamping thereby of said cartons.

10. A sealing machine for cartons, boxes and the like, comprising a standard, a support rotatably mounted on said standard, a plurality of forms mounted on said support, an arm pivoted on said support, one end of which is positioned to engage and clamp one of said cartons, a weight mounted thereon for exerting a downward pressure on said carton when said arm is in horizontal position, a cam member having downwardly extending bearing edges and an outwardly extending flange adapted to be engaged by the relative movement of said clamping arm to cause the same to be substantially vertically positioned so as to permit the replacement of carton to be sealed, and a guide member secured on said standard in position to engage the downwardly extending end of said arm and cause the same to move to a horizontal position as it passes said cam member upon the rotation of said supporting means, for causing the engagement and clamping thereby of said cartons.

In witness whereof, I have hereunto affixed my signature.

GEORGE K. HENDERSON.
